INVENTORS:

UNITED STATES PATENT OFFICE.

CLARENCE C. ROBINSON AND HENRY STRELOW, OF VENICE, CALIFORNIA, SAID
ROBINSON ASSIGNOR TO SAID STRELOW.

OIL-BURNER.

1,193,301.

Specification of Letters Patent. Patented Aug. 1, 1916.

Application filed April 11, 1916. Serial No. 90,398.

To all whom it may concern:

Be it known that we, CLARENCE C. ROBINSON and HENRY STRELOW, citizens of the United States, residing at Venice, in the county of Los Angeles and State of California, have invented new and useful Improvements in Oil-Burners, of which the following is a specification.

Our invention relates to improvements in oil-burners in which a mixing chamber is provided for mixing the oil with the water and air; and the objects of our improvements are, to obtain a complete combustion before the fuel leaves the burner assuring a reduction in the expenses and a better heat to the heating surface; to provide a combustion chamber above the jet in the burner; to provide a fan below the combustion chamber for mixing the oil with the air and water and also forming a revolving jet for the oil and water jets; the invention consisting in the construction, combination and arrangement of devices hereafter more fully described and claimed, and illustrated 25 in the accompanying drawing, in which the figure is a vertical section through our device.

Similar numbers refer to similar parts throughout the specification and drawing.

80 The base 1 carries the casing 2 and the connecting-block 3. Mounted in the connecting-block 3 is the standard 4, which is provided with longitudinal channels 5 and 6. Sidewise inserted or secured to the connecting-block are the water supply-pipe 7 and the oil supply-pipe 8 which communicate with the channels 5 and 6 in the standard. For regulating the supply in the pipes, valves, or cocks 9 and 10 are inserted in the 40 pipe lines 7 and 8. An air-supply tube 11 is secured sidewise to the casing 2. The upper end of the casing is reduced to form the jet 12. A suitable distance below the jet, a combustion-pan 13 is secured to the casing 45 having an upwardly extending edge 13^a formed thereon. Centrally in the jet turnably mounted on the standard is a revolving fan 14, consisting of the cylindrical body 15, the top plate 16 and the vanes 17. A supporting pin 18 is formed on the top end of the standard reducing the friction between the fan and the standard, as the fan is riding on the pin with the top-plate 16. A combustion chamber cap 19 covers the whole 55 burner resting on the leg-members 20 be-

ing thereby spaced from the combustion-pan 13. Air can be forced into the air supply tube 11 by suitable machinery to produce the proper speed on the fan 14, and, in revolving the fan at such a speed, cause a certain centrifugal ejection of the liquid from the channels in the standard through the jet openings 21 in the cylindrical body 15 of the fan 14. The liquid is ignited by throwing a burning piece into the air supply tube 11 through the opening 22, a burning piece of paper or wood will answer this purpose. The sleeve 23 is shifted over the opening 22 before the air machinery is set in motion. The air forced into and through the burner will bring the ignited piece past the oil ejected from the jet-openings 21 thereby igniting the oil right above the fan below the combustion chamber cap 19. The combustion chamber 24 formed by the jet 12 and the cap 19 produces a complete combustion as the oil is forced to mix with the water and air in this chamber by the centrifugal ejection of the oil and water in connection with the circulating passing of the air through the fan 14; and, as the action of ignition is accomplished in this combustion chamber, the cap 19 is heated to a red hot condition promoting the combustion in the chamber 24. Through the combustion chamber 24, allowing a good heating of the fuel and assuring a complete combustion, discharging continually an incandescent flame out of the space formed between the cap 19 and the pan 13, this burner is constructed to give an economical service.

Having thus described our invention, we claim:—

1. An oil burner comprising a casing, a jet formed on the termination of the casing, a standard mounted concentrically in the casing and the jet, said standard provided with channels, fuel supply-tubes communicating with the channels in the standard, an air supply-tube communicating with the casing, a fan turnably mounted on the standard within the jet opening, a combustion pan formed a suitable distance back from the jet opening, and a cap covering the jet forming a combustion chamber in the burner, a discharge space being formed between the cap and the combustion pan.

2. An oil-burner comprising a casing closed at one end and terminating in a jet at the other end, an air supply-tube communi-

cating with the casing having a lighting opening provided therein, a sleeve slidably mounted on the tube adapted to cover the lighting opening, a standard mounted concentrically in the casing having fuel supply channels therein, fuel supply pipes secured to the casing communicating with the channels in the standard, a fan turnably mounted on the standard within the jet opening, 10 and a cap covering the jet opening forming a combustion chamber between the jet and the cap.

3. An oil-burner comprising a casing terminating in a jet, a standard mounted concentrically in the casing and the jet, said standard provided with channels, a combustion pan formed a suitable distance back from the jet opening, a cap covering the jet

spaced from said pan forming a combustion chamber, a fan consisting of vanes and a cylindrical body, said cylindrical body being turnably mounted on the standard having jet openings therein communicating with the channels in the standard, and a top-plate closing the upper end of the cylindrical body forming the thrust-bearing for the fan. 26 25

In testimony whereof we hereunto affix our signatures in the presence of two witnesses.

CLARENCE C. ROBINSON.
HENRY STRELOW.
